UNITED STATES PATENT OFFICE.

DANIEL B. STAUFF, OF UNIONTOWN, PENNSYLVANIA.

DOOR-HANDLING DEVICE.

1,190,036.

Specification of Letters Patent.

Patented Jul. 4, 1916.

Application filed August 2, 1915. Serial No. 43,295.

To all whom it may concern:

Be it known that I, DANIEL B. STAUFF, a citizen of the United States, residing at Uniontown, in the county of Fayette and State of Pennsylvania, have invented new and useful Improvements in Door-Handling Devices, of which the following is a specification.

My invention relates to a crane designed particularly for use in connection with coke ovens for the purpose of handling the doors thereof.

The object of the invention is to provide a device of this character by means of which the doors of ovens may be readily and conveniently opened or closed or otherwise handled.

A further object of the invention is to provide an apparatus of the character described in which the crane is mounted upon a frame and wheeled truck or car which is movable along a trackway to permit the crane to be brought into alignment with the oven doors.

25 A further object of the invention is to provide an apparatus of the character described in which provision is made for the convenient adjustment and manipulation of the crane to facilitate and render easy the operations of handling the doors and adjusting the sprinklers.

With these and other objects in view, the invention consists of the features of construction, combination and arrangement of parts herein fully described and claimed, reference being had to the accompanying drawings in which:—

Figure 1 is a vertical transverse section through the truck and a portion of an oven, 40 and showing the crane disposed in operative position. Fig. 2 is a side elevation on an enlarged scale of the crane *per se*. Fig. 3 is a top plan view of the crane. Fig. 4 is a detail cross section on the line 7—7 of Fig. 45 2. Fig. 5 is a similar view on the line 8—8 of Fig. 2. Fig. 6 is a vertical section through the upper portion of the jack. Fig. 7 is a vertical section through the lower portion of the jack.

50 In carrying my invention into practice, I provide a car or truck 1, comprising a truck frame 2 having a suitable floor 3 and provided with supporting wheels 4 to rest and travel upon track rails 5 arranged parallel with the front wall 6 of a series of bee-hive ovens, provided with the doorways 7 and

doors 8, the latter being hingedly and detachably mounted in the usual way. As is well known, doors of ovens of this character are comparatively heavy and difficult to handle, either in opening or closing the same or in removing the doors for repairs or other purposes. In "drawing the oven" at the end of the coking operation, it is first necessary to open the doors and then to cool the inclosed body of coke by subjecting the same to the action of water. It is customary in such cases to open the oven door and then introduce a watering device by which a spray or streams of water are directed upon the surface of the body of coke to cool the same, such watering devices being commonly handled directly by the workmen, making the operation slow, tedious and laborious.

75 The particular purpose of my invention is to provide an apparatus by means of which the doors of one or more ovens of a series may be quickly and conveniently opened, closed, removed or replaced in successive order, as occasion may require, through the medium of a crane which is movable from door to door and is adjustable as occasion requires and conveniently operable to enable the door to be handled in an easy manner. 85

The car 1 supports an upright frame, preferably made, like the truck frame, of structural steel, and comprising four corner posts 9 connected and reinforced by sets of crossed braces 9' and carrying, below the upper ends thereof, a horizontal overhead frame 10, also made of structural steel elements. This horizontal overhead frame is composed of parallel longitudinal side bars 11, end bars 12 and intermediate bars 13, together with suitable cross braces 14, rendering the frame of great strength and rigidity. The overhead frame may be of any suitable length, and extends in opposite directions beyond the car and the upright frame to 100 approximately equal degrees. Guy rods or wires 15 rest upon or are fastened to the upper ends of the posts 9 and are connected with the outer extremities of the horizontal overhead frame, to further brace and sustain the same from the car and central vertical frame.

Carried by the car is a jack 16, including a bearing sleeve or socket 17, which is adjustable vertically by means of the raising 110 and lowering mechanism of the jack. The jack may be of any suitable character and

construction, but, as shown in the present instance, comprises a fixed hollow base 17^a, telescopically engaged by a vertically movable sleeve or tubular column 17^b, a screw shaft 17^c being inclosed in said base and sleeve and engaging a nut 17^d in the base. At its upper end the shaft carries a beveled gear 17^e meshing with a pinion 17^f carried by a shaft 17^g journaled on the sleeve and provided on the exterior with an actuating crank 17^h, whereby the pinion may be operated to rotate the gear and shaft in one direction or the other, whereby the shaft and sleeve are raised and lowered. The adjustable sleeve or bearing member 17 receives the lower end of a vertical shaft 18 which shaft is rotatable in said sleeve and in a bearing member 19 suitably mounted upon the top of the vertical frame or central portion of the horizontal overhead frame. The shaft 18 is threaded, as at 20, for coöperation with the threaded hub of a hand wheel 21, which is vertically adjustable thereon. This hand wheel serves as a support and adjusting member for a vertically movable horizontal crane arm or frame 22, having upper and lower guide sleeves 23 and 24 slidably and rotatably engaging the shaft and stably supporting the crane arm, the lower sleeve 24 being secured to the crane arm by braces or connecting members 25. It will thus be understood that the crane arm is free to turn or rotate laterally in either direction or with the shaft 18, and may be raised and lowered by adjusting the shaft through the medium of the jack or by adjusting the crane arm on the shaft through the medium of hand wheel 21, this adjusting device allowing the crane to be disposed at any desired elevation for use.

The main crane arm 22 is preferably composed of a pair of channeled beams 22' secured with their flanges facing each other to form a guideway 26 and a basal slot 27 communicating therewith. Telescopically engaging this guideway 26 is an extension arm 28 movable on friction rollers 29 and having rach teeth 30 for engagement with a pinion 31 on a shaft 32 provided with a crank or the like 33, whereby the said extension arm may be adjusted inwardly and outwardly to vary the length of the crane arm. The extension arm carries at its outer end a hook 34 of suitable form to engage the handle 35 of the oven door 8, whereby the crane may be connected with the door for various operations. It will be seen that the extension arm is adapted to be projected so that its hook 34 may slidably engage the door handle, and that the crane may be raised and lowered, as occasion may require, for engagement with the handles of doors at different elevations, or to enable the door to be raised off its base for detachment, or lowered for replacement in position, or dis-

posed so as to be suspended when not in use either from the crane or some suitable supporting means on the oven wall. Also it will be seen that the crane may be swung laterally on its shaft as an axis to swing the door to open and closed positions, in which operations the extensions arm slides along the guideway and also the lever 35 to conform to the arc of movement of the door. By the movement of the apparatus along the track 5 it will be evident that the crane may be brought to a position in line with any one of the doors for coöperation therewith.

Hinged or pivoted to the outer end of the extension arm, as at 34', is a pendent head or pressure member 35 movable by means of a hand lever 36', by means of which the door hung upon the hook may be supported and gently but firmly pressed to its seat in the oven opening.

In practice, the apparatus may be constructed and adapted so as to be conveniently drawn or pushed along the track and arranged so that the crane may be employed to open, close, remove or apply any of the doors, or for successively opening doors and subsequently closing them prior to the operation of cooling a charge of coke and later sealing the oven for the succeeding coking operation. It will be obvious that by means of the improved apparatus these operations may be performed with ease and facility and with a minimum amount of labor on the part of the attendants.

I claim:

1. In a device for handling coke oven doors, the combination of a wheeled supporting frame, a post upon the frame, a crane arm mounted upon the post for vertical adjustment and horizontal swinging motion, said arm being provided with a guideway, an extension arm movable in said guideway, means for vertically adjusting the crane arm, means for moving the extension arm in and out of the guideway, door engaging means on the outer end of the extension arm, and a swinging door controlling device on said extension arm.

2. A device of the character described comprising a wheeled truck, a vertically disposed screw shaft, a jack carrying said mast and operative to raise and lower the same, a crane carried by the mast, means engaging the threaded portion of the shaft for supporting the crane and raising and lowering the same in combination with or independently of the jack, and door engaging means supported by and adjustably mounted on the crane.

3. A device of the character described including a wheeled support, a vertical post upon the support, means for vertically adjusting said post, a crane arm adjustably mounted on the post, means for adjusting

- said crane arm, an extension arm upon the crane arm provided with a door engaging hook, a presser head pivoted to and hanging pendent from the hook, and a lever for operating said presser head.
4. A device of the character described comprising a wheeled support, a post upon the support, a crane arm pivotally and adjustably mounted upon the post, said arm comprising spaced channeled beams forming a guideway and a slot communicating therewith, an extension arm provided with wheels or rollers and movable in said guideway, said arm being also provided with rack teeth upon the underside thereof, a gear arranged within said guide slot and operative for engagement with said rack teeth, a door engaging hook upon the outer end of the ex-
- 10 tension arm, and a door engaging device pivotally supported from said hook. 20
5. A device of the character described comprising a transportable frame, a mast upon the frame, a crane arm adjustably and pivotally supported by said mast, an extension arm upon said crane arm, means for controlling said extension arm, door engaging means upon the extension arm, and means upon the extension arm for forcing the door to a closed position. 25
- In testimony whereof I affix my signature 30
in presence of two witnesses.
